MOUNTING FOR WALLBOARDS

Harry H. Burson, Chicago, Ill.

Application April 15, 1936, Serial No. 74,457

7 Claims. (Cl. 72—46)

This invention is directed primarily to the construction of interior walls or partitions for offices or the like in which it is desirable to make provision for the quick erection of partition walls of light construction, and located in the most convenient positions irrespective of the main structure of the building. For this purpose the present invention employs light studdings, the ends of which are secured by specially formed 10 clips to the floor and ceiling of the room in conjunction with intermediate clips secured to the studdings, which clips afford the means for securing the sections of wallboard or sheathing in position, and at the same time provide space for 15 the location of piping, electrical wiring, or other interior fittings.

The invention is one which employs a set of clips which may, without alteration, be used either to secure the sections of a single wall or 20 to afford an interlocking connection for intersecting walls, so that the intersection may be located at any convenient point without the provision of special clips or fittings designed particularly for this purpose.

25 Further objects and details will appear from a description of the invention in conjunction with the accompanying drawings, wherein—

Figure 1 is a perspective view of intersecting partitions with one of the faces partially broken away to reveal the clips of the present invention;

30 Fig. 2 is a vertical sectional view through the partition wall at a point adjacent one of the studdings;

Fig. 3 is a sectional elevation illustrating the 35 method of employing the clips during the erection of the partition;

Fig. 4 which is a view similar to Fig. 2 shows a modified partition structure in which an intermediate wall is used;

40 Fig. 5 is an enlarged perspective view of one of the intermediate wall section clips;

Figs. 6 and 7 are plan views of the clip illustrating the method of interlocking the same with the studding;

45 Fig. 8 is a view of a metal blank in flat form as used for the modified form of clip in the partition structure of Fig. 4;

Fig. 9 is a plan view of interlocking clips illustrating the use of the clips for wall intersections;

50 Fig. 10 is a plan view of one of the ceiling or floor clips;

Fig. 11 is a perspective view of the same; and

Fig. 12 is a perspective view of a partition intersection showing the wall clips in interlocking 55 relation.

The partition or double wall of the present invention is constructed by the use of vertical studdings 20 which, as shown, are of channel formation comprising a body or web section 21 and edge flanges 22. The studdings are of relatively 5 light material and are ordinarily located about 16" apart, and each of the studdings is secured at its upper and lower ends by the provision of end clips 23, each of which as best shown in Figs. 10 and 11 comprises a rectangular body 10 portion 24 having opposite edges offset to afford parallel flanges 25, each of which is outwardly struck to afford a channel base 26. The medial portion of the channel base is extended outwardly to afford an attaching tongue 27 which 15 is secured by nails or the like to the floor or ceiling as the case may be, while the metal contiguous to the tongue 27 is struck upwardly to afford a pair of separated, aligned channel tongues 28 which in conjunction with the flanges 20 25 afford interrupted channels along parallel edges of the clip for the reception of the edge of a wallboard or panel 29.

The end of the studding is entered through a generally rectangular aperture 30 formed in the body 24 of the clip, which aperture extends inwardly from one edge of the body to a point about half way of the width of the body, and its outer end merges into a slot 31 in the flange 25. The slot 31 is of lesser width than the aperture 30 30 which provides a shoulder 32 afforded by the inward projection of the flange 25.

One of the edge walls of the aperture 30 is inwardly extended to afford a tongue 33 which is initially struck upward to permit the clip as a 35 whole to be easily fitted upon the end of the studding, the parts being positioned so as to bring the tongue 33 adjacent the body or web 21 of the studding, and to bring the studding flanges 22 into contiguous relation respectively with the 40 inner edge of the aperture 30 and with the shoulder 32. After the parts have been positioned, the tongue 33 is struck downwardly which forces it against the body of the studding, thereby 45 clamping the parts tightly together. With the parts thus positioned the clips may be secured to the floor or ceiling by the use of nails driven through holes 34 formed in the attaching tongues 27. In thus attaching the clips, the outer faces 50 of the channel walls 26 will furnish points of contact with the floor or ceiling, thereby holding the body of the clip in spaced relation thereto and in position to afford engagement with the studding at an appreciable distance from its end, 55

so that the possibility of displacement will be obviated.

The studdings may be additionally reinforced by the provision of stringers 35 which extend transversely of the studdings and are secured thereto by wire clips 36. The sections of wallboard 29 at their meeting edges are secured by intermediate clips of the form best shown in Figs. 5, 6 and 7. Each of these clips is of skeleton formation comprising a medial body bridge 37 whose length (transversely) is equal to the extreme width of the clip. The medial body bridge is supplemented by end bridges 38 of equal length, and in the form shown the clip employs two of such end bridges, although it might be elongated to include an additional number of like formation. The overall width of the clip is equal to the space between the outer or exposed faces of the wallboards, the meeting edges of which rest against channel strips 39 having two sets of staggered tongues 40 struck upwardly and downwardly therefrom near the outer ends of the channel strips in conjunction with inner tongues 41 struck upwardly in the same direction on opposite sides of a medial tongue 42 struck downwardly from one end of the medial bridge 37.

The opposite end of the medial bridge is provided with an aperture 43 which is similar in dimensions and configuration to the aperture 30 in the terminal clips, and one edge of the aperture 43 is provided with a tongue 44 which normally stands at an angle to the plane of the medial bridge, but is adapted to be struck downwardly to engage the web of the studding. The aperture 43 is inwardly shouldered near its outer end at the point 45 and the aperture emerges into an edge slot 46 through the contiguous channel strip 39, the edges of which are struck downwardly to afford marginal tongues 47 beyond which the edges are struck upwardly to afford tongues 48 comparable in function to the corresponding tongues 42 and 41 on the opposite edge of the clip.

The arrangement is one which affords oppositely facing interrupted channels along each side edge of the strip to receive the contiguous edges of the wallboard sections and hold the same in edgewise relation within the same plane. The end bridges 38 are of a width substantially equal to the width of the channels thus afforded, so that where it is necessary to provide for a wall intersection, as in Fig. 12, one of the clips, designated A, will be interlocked with the contiguous clip B extending transversely thereto by laying the end bridge 38 of the clip A within the medial portion of the channel afforded by the clip B, which arrangement enables the wallboard sections which are positioned by the clip B to extend continuously through the intersecting region, and permits vertical edges of the wallboard sections engaged by the clip A to abut against the faces of the first mentioned wallboard sections and thus afford a firm and accurate joint at the point of intersection.

By the provision of the edge slot 46 in the intermediate clip sections, the latter can be adjusted to any desired position after the studdings are in place by slipping the clip laterally upon the studding which is entered through the slot 46 and into the aperture 43, which latter is of sufficient width beyond the shoulder 45 to permit the clips to be easily positioned upon the studdings, after which the tongue 44 will be struck down against the web of the studding which holds the same interlocked within the space adjacent the

shoulder 45, thus affording a tight interlock and maintaining the clips in position to bring the studding closely adjacent the wall sections on one side of the clip while affording considerable space between the studdings and the wall sections on the opposite side of the clip which thus provides for the location of pipes P, conduits, or the like within the space thus afforded, as indicated in Figs. 1 and 2.

In the erection of the wall it will ordinarily be found convenient to completely build up one face of the wall before the opposite face is begun, and in so doing the practice indicated in Fig. 3 will be followed. As each course of the wallboard sections is positioned in closely adjacent relation to the studdings, the intermediate clips will be fitted to the studdings and slipped downwardly into position to engage the upper edge of the wallboard sections, after which the next course will be positioned which serves to lock the clips at the various levels on one side of the wall allowing the clips to project beyond the studdings on the unfinished side of the wall at the right.

Having erected the wallboards on one side of the studdings, a rough plaster coat C may be applied, if desired, to its inside face for purposes of sound insulation or to provide a lining which defines one side of a conduit which is thereby provided interiorly of the partition. Such a conduit may be advantageous in connection with a ventilating or air conditioning system. If the modified structure of Figs. 4 and 8 be preferred, the clips are each formed to provide an intermediate or central channel strip 39 for supporting boards 29 constituting a third wall between the other two, thereby further insulating the partition and subdividing its interior into separate spaces each of which may serve as a conduit.

The clips are formed of sheet metal and are sufficiently flexible to permit the projecting edges thereof to be bent upwardly, as in Fig. 3, to the extent required to permit the wallboard sections on the right side of the wall to be properly positioned in vertically standing edgewise relation, after which the clips are pressed downwardly to flatwise relation, as in Fig. 4, to engage the lower course of wallboard sections. The next course above is then positioned and the wall built upwardly until the ceiling is reached.

Since the outer tongues of the clips are exposed at the joints, it is customary to apply facings 49 of plaster or similar surface finish, although, if desired, battens or similar finishing strips might be secured outside of the exposed tongues to afford the desired finish. The intermediate clips of the present invention afford engagement for the wallboard sections at points contiguous to the studdings, although, as before stated, the clips may, if desired, be made longer than here indicated to extend the points of connection to the region intermediate the studdings although ordinarily such further extension is unnecessary since the stringers 35 are of sufficient width to afford an inner bearing and reinforcement for the wallboard sections to prevent inward bulging or collapse on one side, while the studdings themselves afford the necessary reinforcement and support for the wallboards on the opposite side, and obviously the studdings and stringers can be located in sufficiently close proximity to afford the necessary strength and rigidity to the wall. Furthermore, the plasterboard sections or panels are preferably of a stiff unyielding material so that adequate strength can be given to the wall without excessive reinforce- 75

ment, since it is desired to employ relatively light studdings and stringers of channeled metal bars to secure the necessary rigidity without excessive weight.

5 The invention is one which permits interior partition walls to be readily and quickly erected at any convenient point and to permit the clips to be applied to the required positions as the work progresses without the necessity for stringing or mounting the intermediate clips upon the studdings in advance of the erection of the wall. The clips are easily formed into sheet metal by a stamping operation, and the arrangement is one which permits the clips to be tightly and firmly 10 interlocked with the studdings without the necessity for drilling the latter or employing extraneous attaching means or special tools to provide the interlock. Furthermore, by properly proportioning, the intermediate clips may be employed interchangeably either to secure the courses of a single wall or to provide for the intersection of cross walls, as the case may be.

Although the invention has been described with considerable particularity, it is not the intention 25 to limit the invention to precisely the form shown since modifications may be made therein without departing from the spirit of the invention.

I claim:

1. In wall construction the combination of 30 spaced studdings, an apertured terminal clip for each end of each studding, and having means for securing the clip to a contiguous floor or ceiling, each terminal clip having a channel formed at each of its outer edges and each terminal clip having a tongue formed in the edge of the aperture and adapted to be struck downwardly to impinge against and engage the studding, wallboard sections having their edges mounted within the 35 channels in the terminal clips, intermediate clips having apertures permitting the studdings to run therethrough, and each aperture being provided on one edge with a tongue adapted to be struck downwardly to impinge against and engage the studding and each of the intermediate clips having along opposite edges means adapted to provide oppositely facing channels to receive the 40 edges of wallboard sections.

2. In wall construction the combination of 45 spaced studdings, an apertured terminal clip for each end of each studding, and having means for securing the clip to a contiguous floor or ceiling, each terminal clip having a channel formed at each of its outer edges and each terminal clip having a tongue formed in the edge of the aperture and adapted to be struck downwardly to impinge against and engage the studding, wallboard sections having their edges mounted within the 50 channels in the terminal clips, intermediate clips having apertures permitting the studdings to run therethrough, and each aperture being provided on one edge with a tongue adapted to be struck downwardly to impinge against and engage the studding and each of the intermediate clips having along opposite edges means 55 adapted to provide oppositely facing channels to receive the edges of wallboard sections, and cer-

tain of the intermediate clips having a terminal bridge member of a width to lie within the contiguous channel of a companion intermediate clip at a wall intersection to afford an interlock between said clips and certain of wallboard sections standing in angular relation to one another and engaged by the interlocked clips to afford a 5 wall intersection.

3. In a wall construction the combination of 10 a wall supporting member, interlocking clips associated therewith, each having channel members at its edges and one of the clips having a bridge member of a width adapted to fit within the contiguous channel of the companion clip and wallboard sections standing in angular relation 15 to one another and entered respectively within the channels afforded by the interlocked clips.

4. In a wall construction the combination of 20 a wall supporting member, interlocking clips one of which is secured to said wall supporting member, said clips standing in angular relation to one another, one of the clips having formed along its edge a channel and the other clip having a bridge member adapted to fit within said channel to effect an interlock, a wallboard section having 25 its edge entered within the aforesaid channel, and a wallboard section at an angle to the first and standing in engagement with the edge of the clip having the bridge member to afford a 30 wall intersection.

5. In a wall construction the combination of 35 interlocking clips standing in angular relation to one another, one of the clips having formed along its edge a channel and the other clip having a bridge member adapted to fit within said channel to effect an interlock, a wallboard section having 40 its edge entered within the aforesaid channel, and a wallboard section at an angle to the first and standing in engagement with the edge of the clip having the bridge member to afford a 45 wall intersection, one of said clips having an aperture therethrough and a studding entered through said aperture.

6. In a wall construction a terminal clip consisting of a body portion having an aperture extending therethrough in position to receive a studding, the opposite edges of the body portion being struck downwardly to afford inner channel walls and then turned outwardly to afford a 50 channel base, and a portion of the margin end of the base being struck upwardly to afford a channel tongue and a portion being extended outwardly within the plane of the channel base to afford an extension adapted to provide for the attachment of the clip to a floor or ceiling. 55

7. In a wall construction the combination of 60 wall supporting members, a pair of clips associated therewith and each having elements which provide a channel, means on one clip extending into the channel of the other clip for interlocking therewith, the channel of said last named clip being continuous, and wallboard sections standing in angular relation to one another entered respectively within the channels afforded by the 65 interlocked clips.

HARRY H. BURSON.
